UNITED STATES PATENT OFFICE.

HENRY J. HEDLER, OF OCCUM, CONNECTICUT, ASSIGNOR TO DRAPER CORPORATION,
OF HOPEDALE, MASSACHUSETTS, A CORPORATION OF MAINE.

FILLING CLAMPING AND PARTING MEANS FOR LOOMS.

1,427,380.

Specification of Letters Patent. Patented Aug. 29, 1922.

Application filed July 16, 1921. Serial No. 485,383.

To all whom it may concern:

Be it known that I, HENRY J. HEDLER, a citizen of the United States, and resident of Occum, county of New London, State of Connecticut, have invented an Improvement in Filling Clamping and Parting Means for Looms, of which the following description, in connection with the accompanying drawing, is a specification, like characters on the 10 drawing representing like parts.

This invention relates to an automatic filling replenishing loom wherein upon occurrence of substantial exhaustion of the running filling, a fresh filling carrier is 15 automatically transferred from a supply of fresh filling carriers mounted on the loom to the lay and the substantially exhausted filling carrier is ejected from the lay. In this type of loom it is desirable and usual to 20 provide a filling clamping and parting mechanism which acts automatically to clamp the filling extending from the selvage of the cloth to the filling carrier to be abandoned, part the end and carry it forward 25 into the field of action of the usual temple thread cutter which severs the filling end close to the selvage.

The filling clamping and parting means usually has as its support, upon which it is 30 mounted and carried into and out of operative position, the familiar shuttle feeler. This shuttle feeler is usually constituted as a pivoted arm which not only has a swinging movement toward and from, or trans- 35 versely of, the lay but also a movement longitudinally of the lay. One of the problems in mechanism of this type is to secure accurate and efficient operation of the filling clamping and parting means at the required 40 time.

The object of this invention is to provide a simple, accurate and efficient means for operating the filling clamping and parting means upon the operation of the means for 45 transferring the fresh filling carrier from the magazine to the lay.

The object of the invention further is to provide a flexible connection extending between the filling clamping and parting means and an actuating element moved upon the operation of the transferring means.

The object of the invention further is to provide such a flexible connection which will 55 flex both in a direction transversely of the

lay and in a direction longitudinally of the lay.

The nature and object of the invention will appear more fully from the accompanying description and drawings and will be 60 particularly pointed out in claims.

In the drawings:

Fig. 1 is a view in vertical cross section looking from the interior toward the side of an automatic filling replenishing loom embodying a preferred form of the present invention and with only those parts shown which are necessary to a disclosure of the invention.

Fig. 2 is a view similar to Fig. 1 with 70 many of the parts omitted and showing the mechanism in a different position.

Fig. 3 is a top plan view of a portion of the mechanism showing the parts added to the loom to embody a preferred form of the 75 present invention.

Fig. 4 is a top plan view of the loom at the transfer side with only those parts shown pertinent to the invention.

The invention is shown as embodied in an 80 automatic filling replenishing loom of the well known Northrop type and as this type of loom is well known and familiar to those skilled in the art, it is unnecessary to describe or illustrate in detail the general construction and operation of the loom or anything more than those elements directly concerned with the present invention.

Such a loom comprises the usual frame 1, the lay 2 mounted to swing toward and from 90 the breast beam 3, the magazine 4 containing the supply of fresh filling carriers herein shown as bobbins 5 and rigidly secured to the frame or breast beam 3 and the shuttle 6 which is picked back and forth on the lay. 95

In this type of loom when the filling on the filling carrier in the shuttle 6 has become substantially exhausted suitable mechanism acts to rock the shaft 7 extending at the front of the loom. The rocking of this 100 shaft raises the arm 8 and this arm in turn actuates the usual shuttle feeler 9. This shuttle feeler is in the form of an arm pivoted to the frame at 10 to swing toward and from or transversely of the lay. This arm 105 also slides on the pivot 10 and is given its sliding movement by the cam 11 so that it also moves longitudinally of the lay. The main function of the shuttle feeler is to ascertain if the shuttle is properly boxed at 110

the transfer side of the loom. If it encounters the shuttle by reason of the shuttle not being properly boxed, it acts to prevent the operation of the transferring mechanism. This result is secured because the operation of the transferring mechanism is controlled by the shuttle feeler. For that purpose, in the form illustrated, a slotted link 12 is pivotally mounted on the shuttle feeler at 13 and engages a dog 14 pivoted to an arm 15 depending from the usual transferrer arm 16 which is pivotally mounted on a stud 17 in the magazine stand. When the shuttle feeler swings rearwardly and passes the shuttle, if properly boxed, it acts through the mechanism thus described to raise the dog 14 into the path of a bunter 18 on the lay so that as the lay beats up, the transferrer arm is rocked about its stud 17 and effects in a familiar manner the transfer of a fresh filling carrier from the magazine to the lay, or in this case into the shuttle 6 on the lay.

The filling clamping and parting means illustrated is also of a usual familiar type and, as is usual, is supported and carried by the shuttle feeler arm 9. This filling clamping and parting mechanism is shown as comprising a pair of fixed blades 19 and an intermediate movable or pivoted blade 20 all secured to the rearward end of the shuttle feeler arm, the movable blade being pivotally mounted at 21. The movable blade is provided with a laterally projecting pin 22 and a pivoted switch cam 23 is mounted on the upward end of an arm 24 extending upwardly from the frame. As the shuttle feeler 9 swings rearwardly the pin 22 engages the bottom of the switch cam and the movable blade is swung to open position or that position shown in Fig. 2. When the shuttle feeler swings forwardly the pin 22 striking the switch cam swings the switch cam forwardly and passes beneath the same.

45 When transfer of a fresh filling carrier takes place it is necessary to sever the filling end running from the selvage to the abandoned filling carrier and then to carry this end forwardly into the path of the usual temple thread cutter 25 so that it will be severed close to the selvage, accordingly, the filling clamping and parting means must act upon transfer taking place to clamp and sever the filling adjacent the nose of the 50 shuttle and then as the clamping and parting means swing forwardly holding the severed end extending to the fell, the filling clamping and parting means must move bodily longitudinally of the lay or toward 55 the selvage so as not to break the filling end until it is carried safely into the field of action of the temple thread cutter.

The present invention is concerned particularly with the closing movement of the filling clamping and parting means and with

the provision of mechanism for insuring an accurate and efficient closing movement upon transfer taking place. In the construction illustrated this movement is preferably effected directly from the transferrer arm. 70

A suitable bracket 26 is secured as by the bolt 27 rigidly to the frame of the loom, being in this case secured to the flange 28 of the magazine stand, which in turn is secured to the breast beam 3. This bracket extends 75 forward of the magazine stand and is provided at each side with upturned flanges 29 and 30. In these flanges is mounted a transverse shaft 31 having at one end rigidly secured thereto a depending arm or finger 32 80 contacting at its lower end with the depending arm 15 of the transferrer arm 16 when the transferrer arm is in normal or elevated position and having near the other end an upwardly projecting arm or finger 33. In 85 a forward extension of the flange 30 is secured a transverse stud 34 on which is pivotally mounted a rearwardly projecting arm 35 which rests upon and is supported by the arm or finger 33. This arm 35 is herein 90 termed an actuator because it is utilized as the means for actuating the filling clamping and parting means and receives its actuating movement from the transferrer arm through the mechanism described. 95

A direct flexible connection is provided between this actuator arm 35 and the filling clamping and parting means, and in this case the movable member or blade of the filling clamping and parting means. This 100 flexible connection may take various forms and may be made of any suitable material. Preferably it is a flat leather strip 36 with its upper end clamped in a generally horizontal plane to the rear flat end of the arm 105 35 by the bolt 37 and washer 38 and with its lower end secured in a generally vertical plane to one side of the movable blade 20 as by the pin 39.

When now transfer of a fresh filling carrier is to be effected and the shuttle feeler is swung to rearward position, as shown in Fig. 2, and the lay beats up and the bunter 18 strikes the dog 14, the transferrer arm is rocked. The depending arm 15 of the transferrer arm thereupon acts to rock the shaft 31 and raise the actuator 35. Thereupon a direct pull is given through the flexible connection 36 to close the movable member 20 of the filling clamping and parting means 110 and effect the operation of that mechanism. 115

It will be observed that the flexible connection 36 readily flexes both in a direction transversely of the lay and in a direction longitudinally of the lay so that during all movements of the shuttle feeler with the supported filling clamping and parting means, the permanent connection between the filling clamping and parting means and the actuator is effectively preserved. 120 125 130

There is thus presented a simple, efficient and accurate means for operating the filling clamping and parting means upon operation of the transferring means.

5 Having thus described my invention, what I claim as new and desire to secure by Letters Patent, is:

1. An automatic filling replenishing loom comprising a frame, a lay, a magazine for the supply of fresh filling carriers, means for transferring a fresh filling carrier from the magazine to the lay, a support movable toward and from the lay, filling clamping and parting means mounted on the support, 10 an actuator movably mounted on the frame and moved by or through the operation of the transferring means, and a flexible connector extending between and attached to the actuator and the filling clamping and parting 15 means to effect the operation of the latter upon the operation of the transferring means.
2. An automatic filling replenishing loom comprising a frame, a lay, a magazine for the supply of fresh filling carriers, means for transferring a fresh filling carrier from the magazine to the lay, a support movable toward and from the lay and longitudinally of the lay, filling clamping and parting 20 means mounted on the support, an actuator movably mounted on the frame and moved by or through the operation of the transferring means, and a connector extending 25 between and attached to the actuator and the filling clamping and parting means and flexible both in a direction transversely of and in a direction longitudinally of the lay to effect the operation of the filling clamping and parting means upon the operation 30 of the transferring means.
3. An automatic filling replenishing loom comprising a frame, a lay, a magazine for the supply of fresh filling carriers, means for transferring a fresh filling carrier from the magazine to the lay, a support movable toward and from the lay and longitudinally of the lay, filling clamping and parting 35 means mounted on the support, an actuator movably mounted on the frame and moved by or through the operation of the transferring means, and a flat strip of flexible material having its ends secured in planes at right angles to each other, one end to the actuator and the other end to the filling 40 clamping and parting means whereby the said strip flexes both in a direction transversely of and in a direction longitudinally of the lay and acts to effect the operation of the filling clamping and parting means upon 45 the operation of the transferring means.
4. An automatic filling replenishing loom comprising a frame, a lay, a magazine for the supply of fresh filling carriers, a trans- 50 ferrer arm movably mounted on the frame and acting when moved to transfer a fresh filling carrier from the magazine to the lay, a support mounted on the frame to move both toward and from the lay and in a direction longitudinally of the lay, filling 55 clamping and parting means mounted on the support and including fixed and movable blades, an actuator pivoted on the frame and rocked by or through the operation of the trans- 60 ferrer arm, and a flexible connector ex- 65 tends between and attached to the actuator and the movable blade and acting to effect the operation of the movable blade upon the operation of the trans- 70 ferrer arm.
5. An automatic filling replenishing loom comprising a frame, a lay, a magazine for the supply of fresh filling carriers, a trans- 75 ferrer arm movably mounted on the frame and acting when moved to transfer a fresh filling carrier from the magazine to the lay, a support mounted on the frame to move both toward and from the lay and in a direction longitudinally of the lay, filling 80 clamping and parting means mounted on the support and including fixed and movable blades an actuator pivoted on the frame and 85 rocked by or through the operation of the trans- 90 ferrer arm, and a connection extending between the actuator and the movable blade and flexible both in a direction transversely of and in a direction longitudinally of the lay and acting to effect the operation of the 95 movable blade upon the operation of the trans- 100 ferrer arm.
6. An automatic filling replenishing loom comprising a frame, a lay, a magazine for the supply of fresh filling carriers, a trans- 105 ferrer arm movably mounted on the frame and acting when moved to transfer a fresh filling carrier from the magazine to the lay, a support mounted on the frame to move both toward and from the lay and in a direction longitudinally of the lay, filling 110 clamping and parting means mounted on the support and including fixed and movable blades, an actuator pivoted on the frame and rocked by or through the operation of the trans- 115 ferrer arm, and a flat strip of flexible material having its ends secured in planes at right angles to each other, one end to the actuator and the other end to the movable blade whereby the movable blade will be actuated upon the operation of the trans- 120 ferrer arm.

In testimony whereof, I have signed my name to this specification.

HENRY J. HEDLER.
